(57) CLAIM

The ornamental design for a display screen or portion thereof with icon, as shown and described.

DESCRIPTION

The FIGURE is a front view of a display screen or portion thereof with icon showing the claimed design.

The broken lines in the FIGURE show a display screen or portion thereof, and form no part of the claimed design.

1 Claim, 1 Drawing Sheet

UNITED STATES PATENT AND TRADEMARK OFFICE
CERTIFICATE OF CORRECTION

PATENT NO. : D814,514 S
APPLICATION NO. : 29/563718
DATED : April 3, 2018
INVENTOR(S) : Dye et al.

It is certified that error appears in the above-identified patent and that said Letters Patent is hereby corrected as shown below:

In the "Title" item (54), replace "DISPLAY SCREEN OR PORTION THEREOF WITH ICONS" with --DISPLAY SCREEN OR PORTION THEREOF WITH ICON--.

In the "Claim" item (57), replace "The ornamental design for a display screen or portion thereof with icon, as shown and described." with --The ornamental design for a display screen or portion thereof with icon as shown and described.--.

Signed and Sealed this
Third Day of July, 2018

Andrei Iancu
Director of the United States Patent and Trademark Office
